UNITED STATES PATENT OFFICE

HALE PAXTON, OF SANGER, CALIFORNIA

BOX-MAKING TABLE

Application filed July 21, 1928. Serial No. 294,338.

My invention relates to box nailing machines, and more specifically to the table, or tables, adapted to support the shook when assembled to form a box and while the box is being nailed.

It is well known that the depth of a box frequently varies from its width, and in box nailing machines in which the nail driving mechanism has an approximately fixed position, or an adjustment of one or two inches only, it is necessary to have a plurality of tables at various levels so that the box can be positioned on its end or on its side directly under and adjacent to the nail driving device for the purpose of nailing the box.

The objects I have attained in my present invention are the construction of a plurality of box nailing tables which can be selectively, readily and easily adjusted in operative relation with the nailing device, and when so adjusted the table is rigid and adapted to withstand pressure. Other objects are cheapness of construction, simplicity of the device, ease with which it can be manipulated, and other objects to be hereinafter disclosed.

It is here noted that this application is one of a series of applications being filed by me for different features of box nailing machines.

In the drawing accompanying this specification, Figure 1 is a front view of the nailing table showing the ends and a side of the box positioned on the fixed table for nailing and showing the adjustable tables in inoperative position.

Figure 2 is a duplicate of Figure 1 showing the box form positioned for nailing the bottom thereon and showing the upper table positioned in operative relation with the nailing device.

Figure 3 is a side view of the nailing table. The view shown is on the right side of Fig. 2.

Fig. 4 is a view of the inside of the machine along the broken line 4—4 in Figure 2, showing units of each box nailing table.

In the drawing I have shown a frame consisting of upright posts 10 and 11, having base members 12 and 13. Cross beams 14 and 15 are attached to said upright posts on opposite sides thereof and on a common plane

a spaced distance from the base. Cross beams 14 and 15 form a rigid support for the nailing tables hereinafter more specifically described.

Three tables are shown. The lower, or fixed table is formed of bars 17 and 170, resting upon and supported on pairs of blocks 20 and 200. One of each of the pairs of said blocks rests upon cross beam 14, and one of each pair on cross beam 15. As shown in the drawing, blocks 20 support bar 17, and blocks 200 support bar 170.

The upper, and the intermediate tables are selectively adjustable to operative and to inoperative positions. Each of said adjustable tables are formed of two cooperating units. The unit consisting of uprights 24 and cross support 21, and unit consisting of uprights 240 and cross support 210 form the intermediate table, and units consisting of upright supports 26 and 260 with the cross supports 22 and 220 form the upper table. It is here noted that a plurality of adjustable tables constructed similar in form and adapted to cooperate with the other tables in the same manner as the upper and intermediate tables are adapted to cooperate, can be added to the machine without departing from the spirit of my invention.

Referring to the intermediate table, one of said units consists of two upright supports 24, having a cross member 21 attached to said upright supports, said combination forming one side of a nailing table. Upright supports 24 are pivotally mounted on cross beams 14 and 15 a spaced distance from cross member 21. In Figures 3 and 4 are shown a plurality of holes 270, intended for bolting, or otherwise attaching cross members 21 at a selective height from pivot 18.

The cooperating left unit has parts corresponding to those described as forming the right unit 24. Above pivot 19, upright support 240 is the counterpart of upright support 24. Cross member 210 is likewise a counterpart of cross member 21. The plurality of holes 270 are for the purpose above noted, and the pivotal member 19 is the counterpart of pivotal member 18. These units are adapt-

ed to swing toward and from each other within defined limits.

The uppermost table shown on the drawing likewise consists of two units. Referring to 5 one of said units, it consists of two upright supports 26 having a cross support 22. Supports 26 are pivotally mounted to cross beams 14 and 15, preferably with said pivot 18, so that supports 24 and 26 will swing on a common 10 axial line indicated by pivot 18, and uprights 240 and 260 will swing on a common pivot 19. The upright supports should be assembled with relation to each other so that the longer uprights are on the outside of the 15 shorter ones, and the cross supports should be attached on the sides of the upright supports facing the cooperating cross supports. The lengths of the uprights of each cooperating unit, and the spaced distance from the cross 20 supports to the pivotal mounting of each upright on said cooperating units should be the same.

It is noted that the operative position of the table formed by any two units is had by 25 swinging said cooperating units to positions where the cross supports are a spaced distance apart, which in the drawing is shown to be when the upright supports of said cooperating units are standing vertically.

30 The means for swinging the movable tables into, and out of operative relation with the nailing device is as follows:

Upright support 26 has an extension 27 below pivot 18 to which arm 32 is attached 35 at an angle thereto. A rod 33 pivotally connects arm 32 with a pedal lever 34. The fulcrum 340 is at one end of pedal lever 34, and pedal 341 is at the other end. By means of pedal 341, uprights 26 may be operated 40 to or from a vertical position. To simultaneously move upright 260 to a vertical position, rod 59 pivotally connects extension 27 and upright support 260, extending from a point on upright 260 a spaced distance above 45 pivot 19, to a point on extension 27 a spaced distance below pivot 18.

A compression spring 56 encircles rod 59. A spring stop 55 is attached to the rod 59, and a spring stop 58 is attached to crossbeam 14. 50 When lever 34 is depressed spring 56 is compressed, and when lever 34 is released, the tension of spring 56 draws said connected units of the table into operative relation.

To hold the table in inoperative position 55 a catch or hook 36 is provided and attached to the base of the device, and is adapted to hold the pedal lever in depressed position. When the lever is released from the catch, compression spring 56 will return the table 60 units to operative position.

The means for moving the intermediate table into and out of operative position is similar in all respects to the means described for moving the higher table into and out of operative position, except that the pedal there-

fore is on the opposite side of the frame. The parts shown on the drawing to accomplish said purpose consists of the extension 53 to upright 240, rod 49 connecting extension 53 to upright 24, compression spring 46, spring 70 stop 45 attached to rod 49, spring stop 48 encircling rod 49 and attached to crossbeam 14, pedal 39, connecting rod 60, and catch 38.

It is also noted that the permanent table is adapted to form a stop in the movement 75 of the adjustable tables so that the units forming the adjustable table cannot move toward each other beyond the vertical position. By this arrangement of elements, when the pedal lever 34 is released from its catch 38, the co-operating units forming the table will move toward each other until in a vertical position and be stopped by permanent table bars 17 and 170. This is the operative position for 80 the table. By depressing the lever the co-operating units move apart and to an oblique position, thus placing the table in inoperative 85 position and out of the way of the lower tables which may be in operative position.

In said drawing 50 and 51 represent the 90 lower portions of the devices for driving the nails. These are shown to illustrate the relation between the box nailing tables and said nail driving device. In the machine as illustrated the fixed table is used to support the 95 box ends when the sides are being assembled with the ends and are being nailed thereto, and the distance from the table thus used to the nailing device is slightly longer than the 100 length of the box ends, or the width of the box, for the purpose of readily assembling the shock therein. An automatic adjustment on the nailing device positions it on the box. This adjustment will be the subject of another application for Letters Patent.

In the drawing I have shown a box being 105 assembled in which 61 and 610 represent the ends, 62 the side, and 63 the bottom.

When one side of the box is assembled with the ends and nailed thereto, the box is then 110 ready to be positioned on an upper table for placing the bottom thereon. The foot lever is released and the cross beams on the two units forming the table yieldingly engage the ends of the box by means of spring 56. The 115 box form is then pulled forward and the box ends are engaged by two pins or projections 40 and 400 extending inwardly and horizontally near the front end of the cross supports 22 and 220 forming the table. The movement in pulling the box form forward over the projections serves to rock the box form and throw the under edge thereof on a level with the top of the table. When the form is raised on said level spring pressure from 120 spring 56 brings the table assembly against the permanent table used as a stop, and directly under the box ends, which then acts as a support for the box ends. The bottom boards are then assembled with the ends and 125 130

nailed. The foot lever is then depressed, which moves the upper table in inoperative position in which position the lever can be locked by catch 36 and the partly finished box is then dropped to the lower table with the unfinished side uppermost, in which position the shoox is assembled therewith and nailed.

It is noted that in the accompanying drawing there are but two nailing devices shown. This form is preferred because it is easier to drive the nails selectively as to number and position. The box form is moved on the table to position it for driving the nails therein. It is noted that my invention can be used where the nailing device has a plurality of nail driving means as well as in the preferred form I have disclosed in the drawing. Modifications of the box nailing table units can be made by having one upright pivoted support instead of two.

It is also noted that while my description relates more specifically to a box making machine having nail driving means, my invention covers box making machines in which tacks, staples, wire, screws, pins, or their equivalents are substituted for nails in making said boxes.

Having described my invention, I claim:

1. In combination with a box making machine having a device for driving nails, a box nailing table consisting of two unit parts, each part consisting of an upright member pivotally mounted near one end thereof, and having a cross member attached adjacent to the other end of said upright, said pivotal mounting adapting the unit parts to be moved toward and from each other, to a position in operative relation with the nailing device and to positions in inoperative relation with the nailing device, means for moving said units to said operative and inoperative positions, each of said cross members having projections on the front end of cross member, said projections being positioned to face each other.

2. In combination with a box making machine having a device for driving nails, tacks, staples, screws, or their equivalents, a box making table consisting of two unit parts, each part consisting of an upright member pivotally mounted at one end thereof, and having a cross member attached adjacent to the other end of said upright, said pivotal mounting adapting the unit parts to be moved toward and from each other to a position in operative relation with the nailing device and to positions in inoperative relation with the nailing device, means for moving said units to said operative and inoperative positions, each of said cross members having projections positioned on the front end of the cross members, the top of said projections being approximately flush with the top of said cross members.

3. In combination with a box making machine having a device for driving nails,

staples, or screws, a box making table consisting of two unit parts, each unit part consisting of an upright member pivotally mounted at one end thereof, and having a cross support attached adjacent to the other end of said upright, said pivotal mounting adapting the unit parts to be moved toward and from each other to a position in operative relation with the nailing device and to positions in inoperative relation with the nailing device, means for moving said units to said operative and inoperative positions, said cross supports being attached to the sides of the upright members facing each other, and a projection on each cross support on the sides of the cross supports facing each other.

4. In combination with a box making machine having a device for driving nails, a box nailing table consisting of two unit parts, each part consisting of an upright member pivotally mounted at one end thereof, and having a cross member attached adjacent to the other end of said upright, said pivotal mounting adapting the unit parts to be moved toward and from each other to a position in operative relation with the nailing device and to positions in inoperative relation with the nailing device, means for moving said units to said operative and inoperative positions, said cross members being attached to the sides of the upright members facing each other, and a projection on each cross member on the sides of the cross members facing each other, said projection being positioned near the front end of the cross members and approximately flush with the upper surface thereof.

5. In a box making machine having a nailing device as a part thereof, the combination of a fixed nailing table positioned in operative relation to the nailing device, auxiliary tables consisting of two unit parts, each part having an upright support pivotally mounted and spaced and positioned so that when the unit part is radially moved on said pivotal mounting the fixed nailing table will stop said movement in the one direction when the support is in an approximately vertical position, cross members adapted to form the top of the auxiliary table attached to the upright members on the sides facing each other in such relation thereto that the top faces of said cross members are on a common plane when the upright members are engaged by said stop or fixed table.

6. A box supporting table for an automatic box making machine having a nailing device thereon consisting of two cooperating units, each unit consisting of a pivotally mounted support adapted to swing between fixed points, a cross bar attached to each support so that the two cross bars of said two units are in constant parallel relation and are adapted as the top of said table, means for simultaneously swinging said cooperat-

ing units toward and from each other, stop means adapted to limit the movement of said cooperating units toward each other to a position where said table is in operative relation with said nailing device, said positioning means being operative manually and at will.

7. A plurality of box supporting tables of different heights from a common level, for use in connection with a nailing device, each table consisting of a pair of cooperating units, each unit consisting of a pivotally mounted support having cross bars attached so that the cross bars on each unit are parallel with each other and the units of each pair form a table, the units of each pair being of successively different heights, the supports being arranged in relation to each other so that any table can be swung to operative position with said nailing device independently of any of the higher tables, and independent means for manually positioning either of said tables in operative relation with the nailing device.

8. In combination with a nailing device, a plurality of box supporting tables, each table consisting of a pair of units, each unit being pivotally mounted so that the top of a pair of units can be swung to form a common plane in operative relation with the nailing device, said common plane being the top of said supporting table, each of said pair of units being adapted when positioned in said operative relation to be of successively different heights, means for manually and at will positioning either of said tables in said operative relation, and stop means for limiting the movement of the units of each pair of units to the position of operative relation to the nailing device.
